M. L. SOBRA,

TACKLESS WINDOW SHADE.

APPLICATION FILED OCT. 17, 1912.

1,073,447.

Patented Sept. 16, 1913.

UNITED STATES PATENT OFFICE.

MARGUERITE L. SOBRA, OF NEW YORK, N. Y.

TACKLESS WINDOW-SHADE.

1,073,447.

Specification of Letters Patent. Patented Sept. 16, 1913.

Application filed October 17, 1912. Serial No. 726,362.

To all whom it may concern:

Be it known that I, MARGUERITE L. SOBRA, a citizen of the United States, and a resident of the borough of Manhattan, in the county 5 of New York and State of New York, have invented certain new and useful Improvements in Tackless Window-Shades, of which the following is a specification.

My invention relates to means for detachably securing to a roller, pole, or other support, a curtain, window shade, awning, etc., or other flexible sheet of material.

Specifically the invention relates to improvements in a tackless window shade.

15 A further object is the production of a device that is simple and inexpensive, one that can be readily applied to any window shade with very little expense, and one that is not liable to get out of order. It is to be understood, however, that the constructions shown 20 are only a few of a number of forms in which my invention may be embodied, within the scope of the appended claims.

The advantages of the invention are secured by constructions and combinations which are pointed out in the appended 25 claims.

These and such other objects as may hereinafter appear are attained by my device, an embodiment of which is illustrated in the accompanying drawings in which—

Figure 1 represents a fragmentary front elevation of a roller with its window shade, and an exemplification of the invention; 35 Fig. 2 shows a right hand side view of Fig. 1; Fig. 3 shows a top plan view and partial section of Fig. 1 on the line 3, 3; Fig. 4 is an enlarged section of Fig. 1 on the line 4, 4; Fig. 5 represents an enlarged section 40 of Fig. 1 on the line 5, 5; Fig. 6 shows a fragmentary front elevation of a modification of the invention; Fig. 7 represents an enlarged section of Fig. 6 on the line 7, 7; Fig. 8 shows a cross-section of a modified 45 roller for the invention; Fig. 9 represents a side elevation of a retaining strip; Fig. 10 represents a further modification of the invention and Fig. 11 shows a section of Fig. 10 on the line 11, 11.

50 Referring to the drawings a window-shade roller 20 has fitted therewith the usual coil spring not shown. Ferrules or metallic caps 21, 22 with their usual appurte- 55 nances are fastened to the roller 20. The ferrules are slightly bulged at 23 to permit

the entrance therein of the detachable retaining strip 26, which latter is preferably cylindrical in cross-section and of metal. The window shade 30 has formed therein at its upper or inner end a plurality of slots 60 31, and is folded over as shown at 32, with the folded over portion bearing against the roller 20. The cylindrical retaining strip 26 is concavo-convex and formed with a curve slightly larger in diameter than the diameter 65 of the roller 20. It is inserted through the slots 31 of the shade 30. The end portions of the retaining strip 26 bear on the outer surface of the side portions of the shade 30 to securely clamp the latter against the outer 70 surface of the roller. This disposition of the retaining strip prevents the shade from being torn when used. The bulged portions 23 of the ferrules in conjunction with the outer cylindrical surface of the roller form 75 cavities for the ends of the said retaining strip. With this disposition of the retaining strip it is interlaced with the shade 30, so that alternate portions thereof are on opposite sides of the front portion of said shade 80 as shown at 33 and 34.

Referring to Figs. 6 and 7 which represent a modification of my invention, a roller is shown at 36, with the ferrules 37, 38 having the bulged portions 39. The retaining 85 strip 40 is represented interlaced with the shade 41. The shade 41 is folded over at 42 and at the upper end of the fold a reinforcing strip 43, preferably concavo-convex in form, is inserted. The ends of the strip 90 43 enter the bulged portions 39 of the ferrules 37, 38, and screws 44 in threaded engagement with the ferrules may clamp the ends of the strip 40 to more rigidly hold it in place. The reinforcing strip 43 is pref- 95 erably made of metal and does not necessarily require its ends to be inserted in the bulged portions 39 of the ferrules.

In Fig. 8 a roller 50 is represented with the ferrule 51 and a retaining strip 52. The latter is located at its ends in a groove 53 formed in the surface of the roller 50 when it enters the said ferrule, thereby obviating the necessity of bulging the ferrule.

Among the advantages of my invention 105 may be mentioned the detachable function of the retaining strip from the shade and from the ferrules of the roller. The interlacing of the retaining strip with the shade and the detachable locking of the ends of 110

said strip with the ferrules provide a substantial support for the shade and prevents its tearing when using the roller.

Difficulty has been experienced heretofore in finding a sufficient means for securing a window curtain shade in place and one that can be inexpensively manufactured and put in place on the window. By the use of my device a tackless window shade is secured.

10 In the modification shown in Figs. 10 and 11, the roller 60 similar to 20 supports the shade 61 similar to 30. A ferrule 62 has extending therefrom the lip 63 which bears upon the shade 61 covering one of the corners thereof. The retaining strip 64 is not interlaced with the shade but is located in the fold formed by folding over the end of said shade as shown at 65.

Having described my invention what I desire to secure by Letters Patent and claim is:

25 1. In a device of the character described the combination of a roller, ferrules supported on the roller, a flexible sheet of material for the roller, a concavo-convex retaining strip engaged by said ferrules and connecting said sheet of material to said roller, and lips extending from the ferrules each covering one of the corners of the shade.

30 2. In a device of the character described the combination of a roller, ferrules at the ends of said roller, a flexible sheet of material having a plurality of slots for said roller, a retaining strip interlaced with said

sheet of material by extending through the 35 slots thereof and having its ends engaged by said ferrules.

3. In a device of the character described the combination of a roller, ferrules having bulged portions supported on the ends of 40 said roller, a flexible sheet of material with one end bearing on said roller, a retaining strip interlaced with said sheet of material and its ends engaged between the inner walls of the bulged portions of said ferrules 45 and the end portions of the roller.

4. In a device of the character described the combination of a roller, a flexible sheet of material for the roller, a concavo-convex retaining strip interlaced with said sheet of 50 material, maintaining said sheet of material in place with said roller, and a reinforcing strip for said material.

5. In a device of the character described the combination of a roller, a flexible sheet 55 of material for said roller, a concavo-convex retaining strip interlaced with said sheet of material to secure the latter to the roller and means to rigidly hold said strip in place with said roller.

Signed in the borough of Manhattan in the county of New York and State of New York this 15th day of October A. D. 1912.

MARGUERITE L. SOBRA.

Witnesses:

A. A. DE BONNEVILLE,
CHARLES LA RUE.
